LIQUID FLOWMETER

Francis J. Spreitzer, Chicago, Ill.

Application May 14, 1957, Serial No. 46,164

Term of patent 14 years

(Cl. D91—1)

Fig. 1.

Fig. 2.

Fig. 3.

Figure 1 is a front elevational view of a liquid flowmeter showing my new design;

Figure 2 is a top plan view of the flowmeter; and Figure 3 is an end elevational view thereof.

I claim:

The ornamental design for a liquid flowmeter as shown.
